UNITED STATES PATENT OFFICE.

HENRI VICTOR JULES JOUFFRET, OF PARIS, FRANCE.

PISTON FOR ENGINES.

1,153,795.

Specification of Letters Patent. Patented Sept. 14, 1915.

Application filed April 10, 1914. Serial No. 830,984.

To all whom it may concern:

Be it known that I, HENRI VICTOR JULES JOUFFRET, a citizen of the French Republic, residing at 18 Rue de Bruxelles, Paris, France, have invented certain new and useful Improvements in Pistons for Engines; and I do hereby declare the following to be a full, clear, and exact description of the invention, such as will enable others skilled in the art to which it appertains to make and use the same.

This invention relates to pistons and is more particularly applicable to those for rotary motors, since, as far as the inventor has been able to ascertain up to the present, it is in connection with motors of that description that it possesses the most advantages.

The principal object of the invention is to render devices of the class in question more fluid tight or gas tight than has been possible with previous constructions.

The invention consists generally in slotting or splitting devices of the class in question in certain particular methods herein-
25 after more fully explained.

The invention also relates to certain constructional forms hereinafter described and includes, as new industrial products, devices made according to the invention and the 30 special parts suitable for making up such devices.

In order that the invention may be more clearly understood, it will be now more fully described with reference to the accompanying drawing, it being however clearly understood that the description and drawing only refer to one typical method of carrying out the invention.

The drawing shows an axial section of a 40 piston made according to the invention.

According to the particular method of carrying out the invention illustrated on the drawing, which shows a piston for a rotary motor, α is the piston which is extended upward into a truncated conical portion α' of very slight conicity, such portion being hollow or recessed at the upper part, the upward extensions being extremely thin and of an external diameter equal to that of the 50 interior of the cylinder or of slightly larger diameter. The upwardly extending portion is slotted or split so as to divide it into a

certain number of parts the slotting or splitting being preferably effected by means of saw cuts which are as narrow as possible. 55 With this construction the divided portions of the piston, by reason of their elasticity, press against the wall of the cylinder and any escape of fluid can only take place through the cuts, instead of taking place 60 around the whole periphery of the piston, as has been the case with motors as constructed up to the present, as it has been necessary to leave a certain amount of play between the piston and the cylinder for various reasons and in particular on account of the inequality of the rate of expansion of the two parts. The construction according to the invention is of special importance in the case of rotary motors, the cylinders of 70 which tend to become oval, owing to their rotation around the shaft, and this is fatal to their fluid or gas tightness. The devices may be rendered still more fluid or gas tight by means of packing rings in the ordinary 75 way.

It is to be understood that the invention is not limited in any way to the method of carrying the same into effect herein described or to the particular application thereof indicated, as it includes all modifications and applications.

What I claim and desire to secure by Letters Patent of the United States of America is:—

A piston for the cylinder of an engine having at one end an integral hollow extension with a thin yielding wall having an external diameter greater than the diameter of the cylinder in which it is to be fitted 80 and also greater than the external diameter of the remaining portion of the piston, the extension being of truncated conical form and having a plurality of slots formed longitudinally thereof and continuing through 90 the free end edge of the same, the said slots terminating short of the body of the piston adjacent to the hollow extension.

In testimony whereof, I affix my signature, in presence of two witnesses.

HENRI VICTOR JULES JOUFFRET.
